UNITED STATES PATENT OFFICE.

LAON WERTHEIMER, OF NEW YORK, N. Y.

DESIGN FOR A SKIRT-HOLDER PLATE.

SPECIFICATION forming part of Design No. 35,999, dated August 12, 1902.

Application filed March 28, 1902. Serial No. 100,483. Term of patent 3½ years.

To all whom it may concern:

Be it known that I, LAON WERTHEIMER, a citizen of the United States, residing in the city, county, and State of New York, have in-

5 vented and produced a new, ornamental, and original Design for a Skirt-Holder Plate, of which the following is a specification, reference being had to the accompanying drawing, forming part thereof.

10 The accompanying drawing represents a top plan view of my design.

My design, as shown in the accompanying drawing, consists of an ornamental plate C, provided with a ring or loop D at its upper edge, the said plate having upon it the representation of a human head partially surrounded or inclosed by scrollwork. 15

What I claim is—

The ornamental design for a skirt-holder plate, substantially as herein shown and described. 20
